E. E. HINRICHSEN.
TELEPHONE SYSTEM.
APPLICATION FILED SEPT. 25, 1917.

1,277,418.

Patented Sept. 3, 1918.

UNITED STATES PATENT OFFICE.

EDWARD E. HINRICHSEN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,277,418.

Specification of Letters Patent. Patented Sept. 3, 1918.

Application filed September 25, 1917. Serial No. 193,103.

To all whom it may concern:

Be it known that I, EDWARD E. HINRICHSEN, a citizen of the United States, residing at New York, in the county of New York and State of New York, have invented certain new and useful Improvements in Telephone Systems, of which the following is a full, clear, concise, and exact description.

This invention relates to telephone systems and more particularly to such systems of the central energy type provided with apparatus for determining the idle or busy condition of the telephone lines of the telephone system.

15 The object of this invention is to provide an improved busy testing means for such systems. In accordance with this invention, which is an improvement over that disclosed in a copending application of Clarence B.

20 Fowler, Serial No. 193,102, filed September 25, 1917, there is provided a relay which when a busy test is being made is connected in circuit relation with the busy test relay to improve the operation of this busy test relay.

25 When the usual listening key is actuated to connect the operator's telephone set with an established connection between two subscribers, this relay is energized to disconnect the busy test relay from the circuit.

30 For a more complete understanding of this invention reference should be had to the following description considered in connection with the accompanying drawing illustrating one embodiment of this invention.

35 In the drawing there are shown two poly-station telephone lines A and B, which terminate at a central office in a plurality of jacks, and a cord circuit C located at the central 40 office and employed for interconnecting the telephone lines. It is to be understood that many lines similar to lines A and B may terminate at the same central office and that a plurality of cord circuits may be provided 45 for interconnecting such lines, but for convenience only the two lines and the one cord circuit are shown. It is believed that this invention will be thoroughly understood from a description of the operation of the 50 system shown in the drawing and it will be so described.

One of the subscribers on line A in initiating the call removes the receiver from the switchhook, thereby causing the operation 55 of line relay 5, which thereupon causes the

lighting of line lamp 6. The operator upon observing the lighted condition of the line lamp 6 inserts answering plug 7 in one of the jacks associated with the line A, for example, jack 8. Cut-off relay 9 is thereupon 60 operated to disconnect the line relay from the line and to efface the line lamp 6. Answering supervisory relay 11 is also operated upon the connection of the answering plug 7 with the jack 8 to remove the short 65 circuit from resistance 12 and to establish a short-circuit about the answering supervisory lamp 13, thereby preventing the lighting of the lamp when the answering plug is inserted in the jack of the calling line. 70

The operator may now actuate listening key 15 to connect the operator's telephone set 16 with the cord circuit. Assuming that the calling subscriber desires connection with another party on the same telephone 75 line, the operator does not know that this second party is on the same line since there is provided for each station on the line a separate jack, and each station on the line is assigned a separate number. The operator, therefore, tests the line to determine whether it is idle or busy. In making this test, where the called party is on the same line with the calling party, the operator not only obtains the usual busy test, which is 80 merely a single click in the operator's receiver, but in addition there is produced in the receiver a tone which indicates that the called party is on the same line with the calling party. The manner in which this 85 tone is produced in the operator's receiver 90 will now be described.

When the listening key 15 was actuated, contact 17 thereof was opened and contacts 18, 19, 20 and 21 closed. The closure of contacts 19 and 20 connected the operator's telephone set to the cord circuit and the closure of contact 18 connected the busy test relay 25 (common to a plurality of cord circuits) with the tip conductor 26, which is the testing conductor for the calling end of the cord circuit. The closure of contacts 18 and 19 also connected both windings of relay 27 (common to a plurality of cord circuits) 100 in the tip conductor 26 in series with winding 28 of repeating coil 29. In order to provide for the best transmission efficiency to voice currents, the windings of the repeating coil 29 must be of low resistance. 105 Therefore, when the busy test relay is con- 110

nected with the tip conductor it is shunted by the low resistance winding of the repeating coil. It has, therefore, been extremely difficult to obtain a busy test relay which 5 would operate when the tip contact of the calling plug is engaged with the test terminal of a jack. The resistance of the left-hand winding of relay 27 is low and of practically the same value as the winding 10 of supervisory relay 31, while the right-hand winding of relay 27 is of high resistance. When making a busy test both windings of relay 27 are connected in the tip conductor 26 in series with repeating coil winding 28 and very materially increases the resistance of the shunt about the busy test relay 25, so that when making a busy test relay 25 receives a greater amount of current, thereby insuring the proper operation of the 15 relay. With the listening key actuated and the tip of the calling plug 32 brought into engagement with another jack 33 of the calling line A, the busy test relay 25 is operated over a circuit from battery through 20 the resistance 12, sleeve contacts of the answering plug 7 and the jacks 8 and 33, the tip contact of the calling plug 32, tip conductor 26, contact 18 of listening key 15, left-hand contact of relay 27, and the winding of 25 busy test relay 25 to ground. While a circuit through relay 27 is established at the same time, this relay does not receive sufficient current to cause it to attract its armatures. At the same time that relay 25 is 30 operated a surge of current passes through both windings of relay 27 and through the receiver of the operator's telephone set, thereby producing a click in this receiver. Busy test relay 25 in operating connects a 35 source of tone supply 34 with the operator's receiver 38 over a circuit from source 34 through a condenser 35, contact of busy test relay 25, contact 21 of listening key 15, conductor 36, sleeve contacts of the answering 40 plug 7 and jacks 8 and 33, tip contact of calling plug 32, tip conductor 26, contact 18 of listening key 15, windings of relay 27, induction coil winding 37, receiver 38, condenser 39, conductor 40, contact 20 of listening 45 key 15, winding of supervisory relay 31, repeating coil winding 41, through battery to ground. A tone is thereby produced in the operator's receiver 38, indicating to the operator that the called party is on the same 50 line with the calling party. The relay 27 is not sufficiently energized when in the circuit just traced to attract its armatures. The connection with the called line and the signaling of the called station may be 55 accomplished in any desired manner.

If the called party is one of the subscribers on line B, and line B is not busy, the engagement of the tip of the calling plug 32 with the test terminal of one of the jacks 60 of line B does not produce a click in the op-

erator's receiver. The operator thereupon restores the listening key to normal position, and inserts the calling plug 32 into one of the jacks of the line B, whereupon the calling supervisory lamp 45 is lighted and cut-off relay 46 operated. The called party may now be signaled in any desired manner. In responding, the called party removes the receiver from the switchhook, thereby causing the operation of the calling supervisory relay 31 which first removes a short circuit from resistance 47 and establishes a short circuit for calling supervisory lamp 45 which is thereupon effaced.

If, while connection between lines A and B is established, and while the receiver of the called party is removed from the switchhook, the operator actuates the listening key 15 to supervise the connection, the busy test relay 25 is thereupon automatically disconnected from the testing conductor in order not to produce any noise on the line. This is brought about in the following manner: Under the conditions mentioned, when listening key 15 is actuated, the windings of relay 27 are connected in series with the tip conductor 26 in the manner hereinbefore described, and this relay now receives more current, whereupon it operates. The circuit over which this relay 27 operates may be traced from battery through repeating coil winding 41, winding of supervisory relay 31, ring contacts of calling plug 32 and jack 48, through the apparatus and switchhook contact of the called station, tip contacts of jack 48 and calling plug 32, tip conductor 26, contact 18 of listening key 15, windings of relay 27, contact 19 of listening key 15, and repeating coil winding 28 to ground. Relay 27 in operating opens its left-hand contact, thereby preventing the connection of relay 25 with the tip conductor 26, and closes its right-hand contact, thereby to short-circuit its right-hand high resistance winding, which is thereupon removed from the talking circuit. The removal of this high resistance from the talking circuit is for the purpose of preventing the reduction in transmission efficiency. The left-hand winding of this relay, as before stated, is of practically the same resistance as the winding of supervisory relay 31, and when connected in the tip conductor 26, serves to balance the talking circuit. After supervising the connection the operator may restore the listening key 15 to normal position, whereupon the relay 27 is removed from the circuit.

At the conclusion of the conversation the subscribers may restore the receivers to the switchhook, whereupon supervisory relays 11 and 31 release to cause the lighting of the supervisory lamps 13 and 45, which serve as disconnect signals. The operator may then remove the plugs from the jacks 130

whereupon all the apparatus is restored to normal condition.

The windings of relay 27 serve as a resistance coil connected in parallel with the 5 busy test relay 27 when making a busy test to insure the proper operation of the busy test relay. This relay 27 also serves as a disconnect relay for removing the busy test relay from the circuit when the operator is 10 listening in on an established connection between two subscribers. By making it serve the double function, no additional apparatus is required in the circuit and the busy test relay due to the resulting improved 15 operating conditions may be of simple rather than complex construction.

What is claimed is:

1. In a telephone system, in combination, a poly-station telephone line terminating in 20 a plurality of jacks, a cord circuit having its answering end connected with one of the jacks, a testing conductor for the calling end of the cord circuit, a repeating coil for the cord circuit having a winding connected in the testing conductor, an operator's telephone set, a listening key for connecting the operator's telephone set with the cord circuit, a relay connected in series with the repeating coil winding by actuation of 25 the key, a source of tone supply, and a busy test relay connected with the testing conductor and in parallel with the first relay and the repeating coil winding upon the actuation of the key and responsive to the 30 engagement of the testing conductor with the test terminal of another jack to connect the source of tone supply in circuit with the receiver of the operator's set.

2. In a telephone system, in combination, 40 a plurality of poly-station telephone lines, each terminating in a plurality of jacks, a plurality of cord circuits, one of the cord circuits having its answering end connected with a jack of one of the telephone lines, a 45 testing conductor for the calling end of each cord circuit, an operator's telephone set, a listening key for the engaged cord circuit for connecting the operator's telephone set therewith, a relay common to the cord 50 circuits connected in series with the testing conductor by the actuation of the key, a source of tone supply, and a busy test relay connected with the testing conductor in parallel with the first-mentioned relay upon 55 actuation of the key and responsive to the engagement of the testing conductor with the test terminal of another jack of the engaged line to connect the source of tone supply in circuit with the receiver of the operator's telephone set.

3. In a telephone system, in combination, 60 a plurality of telephone lines each terminating in a plurality of jacks, a cord circuit having its answering end connected with a 65 jack of one of the lines, a combined testing

and talking conductor for the calling end of the cord circuit, an operator's telephone set, a listening key for connecting the operator's telephone set with the cord circuit, a source of tone supply, a busy test relay connected 70 with the testing conductor by the actuation of the key and responsive to the engagement of the testing conductor with another jack of the engaged line for connecting the source of tone supply in circuit with the receiver 75 of the operator's telephone set, and a relay connected in series with the testing conductor by the actuation of the key and energized when the calling end of the engaged cord circuit is connected with another telephone line to disconnect the test relay from 80 the testing conductor.

4. In a telephone system, in combination, a plurality of telephone lines each terminating in a plurality of jacks, a cord circuit, a combined testing and talking conductor for the calling end of the cord circuit, a busy test relay adapted to be connected with the testing conductor for determining the idle or busy condition of a line, an operator's 85 telephone set, a listening key for connecting the operator's telephone set with the cord circuit, and a relay connected in series with the talking and testing conductor by the actuation of the key and energized when the 90 calling end of the cord circuit is connected with a telephone line to disconnect the busy test relay from the testing conductor.

5. In a telephone system, in combination, 100 a plurality of telephone lines each terminating in a plurality of jacks, a cord circuit having its answering end connected with a jack of one of the lines, a combined talking and testing conductor for the calling end of the cord circuit, an operator's telephone 105 set, a listening key for connecting the operator's telephone set with the cord circuit, a source of tone supply, a busy test relay connected with the testing conductor by the actuation of the key and responsive to the engagement of the testing conductor with another jack of the 110 engaged line for connecting the source of tone supply in circuit with the receiver of the operator's telephone set, and a disconnect relay having a plurality of windings connected in series with the combined talking and testing conductor and in parallel with the busy test relay by the actuation of the key, said disconnect relay being unresponsive to the engagement of the testing conductor with the test terminal of a jack, but responsive when the calling end of the 115 cord circuit is inserted into a jack of one of the telephone lines to disconnect the busy test relay from the testing conductor and to remove one of its windings from the circuit.

6. In a telephone system, in combination, 120 a plurality of telephone lines each terminat-

ing in a plurality of jacks, a cord circuit having its answering end connected with the jack of one of the lines, a combined talking and testing conductor for the calling end of 5 the cord circuit, an operator's telephone set, a listening key for connecting the operator's telephone set with the cord circuit, a busy test relay connected with the testing conductor by the actuation of the key, and a 10 disconnect relay connected in series with the

combined talking and testing conductor by the actuation of the key and energized when the cord circuit is connected with the jack of another line to disconnect the busy test relay from the testing conductor.

15

In witness whereof, I hereunto subscribe my name this 19th day of September A. D., 1917.

EDWARD E. HINRICHSEN.
